FASTENING INSERTING MACHINE

Fred N. La Chapelle, Beverly, Mass., assignor to
United Shoe Machinery Corporation, Paterson,
N. J., a corporation of New Jersey

Application January 16, 1934, Serial No. 706,887

6 Claims. (Cl. 1—41)

This invention relates to fastening inserting machines and is illustrated herein as embodied in a machine particularly adapted for all-round nailing in the manufacture of boots and shoes.

5 Machines used for all-round nailing in the manufacture of boots and shoes, or for any nailing off the last in which it is desired to clench the nails upon the insides of the shoes, are commonly provided with a work support, for example,

10 a horn having a clenching cavity in its work engaging surface. Such machines, while they ordinarily clench nails satisfactorily, may, under some conditions, deflect the points of the nails outwardly toward the edge of the shoe, causing

15 the nails to penetrate the shoe upper with consequent damage and injury to the shoe. Even when the nails are perfectly clenched on the inside of the shoe the clenched ends of the nails may extend in different directions with the result

20 that the inside of the shoe does not present a neat finished appearance. Furthermore, in such machines the clenching cavities are located at or near the center at the tip of the horn and the nailing operation therefore must ordinarily take

25 place a substantial distance from the edge of the horn, thus locating the nails a substantial distance from the edge of the insole which may, during wear of the shoe, permit the edge of the insole to curl, thereby causing discomfort to the

30 wearer.

It is an object of the present invention to provide a fastening inserting machine having an improved clenching mechanism organized to clench all the fastenings in substantially the same direction and near the edge of the inside of the shoe. In the operation of the illustrated machine this is accomplished by providing an anvil having a clenching surface located near the edge of the anvil with the center of said surface being offset from the axis of rotation of the support on which it is mounted and arranged to remain stationary relatively to the fastening inserting instrumentalities of the machine in order that the points of the nails may strike the clenching surface at a predetermined point, thereby causing the fastening to be clenched in a predetermined direction. In the illustrated machine the work support is rotatably mounted on the frame of the machine in order that the tip of the work support may reach all parts of the inside of the shoe and the horn button is maintained in a predetermined position relatively to the fastening inserting mechanism by gear connections to the frame of the machine.

55 With the above and other objects and features

in view the invention will now be described in connection with the accompanying drawings, which show a machine constituting a preferred embodiment of the invention, and pointed out in the accompanying claims. It should be understood, however, that the machine may be modified in various respects within the scope of the claims without departing from the invention.

In the drawings,

Fig. 1 is a view in side elevation of a portion of a fastening inserting machine embodying the present invention;

Fig. 2 is a sectional view taken along the line II—II of Fig. 1;

Fig. 3 is a sectional view on an enlarged scale of a portion of the horn with the parts in the position shown in Fig. 1;

Fig. 4 is a view in side elevation of a portion of the horn showing the relative position of the parts after the horn has been rotated substantially 180°;

Fig. 5 is a detail plan view of the end of the horn;

Fig. 6 is an enlarged detail view in front elevation of a portion of the horn and the fastening inserting instrumentalities;

Fig. 7 is an enlarged detail view showing the position of the horn when operating about the toe end of a shoe; and

Fig. 8 is a similar view showing the horn operating adjacent to a longitudinal edge of the shoe.

The illustrated machine is of the general type disclosed in United States Letters Patent No. 1,030,775, granted June 25, 1912, on an application filed in the name of George Goddu. The machine may advantageously be equipped, if desired, with a horn pressure relieving mechanism such as that disclosed, for example, in United States Letters Patent No. 1,686,808, granted October 9, 1928, on an application filed in the names of George Goddu and Fred L. Mackenzie. Reference may be had to these patents for a full disclosure of such parts of the machine as it is unnecessary to illustrate or describe herein.

The illustrated machine is provided with a head 10 mounted on a column (not shown). The head 10 is provided with mechanism for operating the fastening inserting instrumentalities of the machine. An awl 12 is reciprocated through connections including a link 14 to a bell crank lever 16 which carries at one end a cam roll arranged to ride in a cam track 18. The awl 12 is mounted for movement toward the work to form fastening receiving holes and is also arranged for move-

45

35

40

45

50

55

ment parallel to the edge of the work to move the fastening receiving holes into alignment with the path of movement of a fastening inserting member or driver 20. The driver 20 is arranged 5 for reciprocating movement toward and from the work through connections to a cam in the manner disclosed in said Letters Patent.

The column of the machine also carries a work support or horn 21 terminating in an anvil 24 which is arranged to support a work piece, for example, a shoe 26 with its sole 28 in engagement with a presser plate or abutment 30 carried by the head of the machine. The position of the shoe relatively to the fastening inserting instrumentalities of the machine may be determined, 15 if desired, by the use of any suitable gage which may also be secured to the head 10 of the machine.

Referring now to Figs. 5, 7 and 8 of the drawings, it will be noted that the anvil 24 is illustrated 20 as provided with an elongated relatively small and narrow clenching cavity 32. The clenching cavity is provided with side walls 33 and 35 which extend substantially parallel to the feed of the work in order that the direction of clench will be substantially parallel to the edge of the shoe. The clenching cavity is formed adjacent to the edge of the anvil 24 to permit the fastenings to be driven as close to the edge of the shoe as is 25 possible and consequently the center of the clenching cavity is offset with respect to the axis of rotation of the horn 21. By the use of this construction the clenching cavity may be made relatively small and effective clenching of the fastenings will be insured. The clenching cavity 32 is arranged to deflect the ends of the fastenings in a direction parallel to the feeding movement of the awl 12, wherefor the direction of the clench of the fastenings may be said to be predetermined with respect to the edge of the shoe or other work piece. The horn or support 21 is firmly secured by clamping screws 38 to the upper end of a horn post 34 which is rotatably mounted in an upstanding portion or projection 36 of the column of the machine. The lower end of the horn post 34 is connected to mechanism for raising and lowering the horn between successive feeding movements of the awl 12 in the manner described in the above-mentioned Letters Patent. 30

In order that the nails or other fastenings shall be clenched in one direction, the position of the clenching cavity 32 relatively to the driver 20 must be constant. That is to say, the clenching cavity must be so located at all times with 35 respect to the driver that the end of the fastening inserted by the driver will strike substantially the same portion of the surface of the cavity 32. When the end of the fastening strikes the inclined surface of the clenching cavity 32, it is deflected toward the deepest portion of the cavity. The direction of clench is thus controlled primarily by the location of the deepest portion of the cavity relatively to the line of drive of the fastening. For example, in Fig. 6, the driver 20 is shown as being located just above the left side 40 of the clenching cavity. Thus, when a fastening is driven through the work, and the point of the fastening engages the surface of the clenching cavity 32, the point of the fastening will be deflected toward the right in the manner shown, for example, in Fig. 7. It is to be noted, that, as 45 shown, the center of the deepest portion of the clenching cavity is located to the right of the line of drive of the fastening but it is evident that 50 the location of the center of the clenching cavity

could be located in other positions relatively to the line of drive, if it were desired to deflect the points of the fastenings in other directions. In order to maintain the horn button 24 and the clenching cavity 32 in the same position relatively to the awl 12 and driver 20, regardless of the position of the horn, the horn button 24 is connected to the frame of the machine by mechanism which will hereinafter be described.

The work support 21 is arranged to rotate about the jack post 34 in order that the tip of the horn may reach all parts of the inside of the shoe. Referring now particularly to Fig. 3, it will be noted that the horn button 24 is provided with a stem or stub shaft 40 which fits into a bearing formed adjacent to the tip of the work support 21. The lower inside portion of the horn button 24 is provided with gear teeth 41 which mesh with gear teeth 43 formed on the end of a shaft 42. The horn button 24 is rotated relatively to the horn 21 by means of the shaft 42 which is connected by an epicyclic train of gears to the frame of the machine. The axis of rotation of the horn button 24 must be coincident with, or in alignment with, the axis of rotation of the horn 21 as will later become apparent. In order to reduce friction between the horn button 24 and the horn 21 a ball bearing unit 44 is interposed between the lower portion of the horn button 24 and the tip of the horn 21.

A gear 46 is secured to the portion 36 of the column of the machine and is held immovably in place. Meshing with the gear 46 is an idler gear 48 rotatably mounted on a stub shaft 49 mounted in the support 21. In order that the gear 48 may conveniently be removed whenever it is necessary to make adjustments or to replace worn or broken parts, the gear 48 is held in operating position by means of a stud 50 which engages an enlarged end portion 53 of the stub shaft 49 and which is threaded into and through a laterally extending portion 52 of the work support 21. The stud 50 is locked in position by means of a lock nut 54. The gear 48 is relatively long to permit the relative vertical movement between the gear 46 and the gear 48. This is necessary in order that the gears 46 and 48 remain in mesh when the horn is raised and lowered between feeding movements of the awl 12.

The gear 48 meshes with a gear 56 formed on the lower end of a shaft 58 which is mounted in a bearing 59 in a vertical portion of the horn 21. The upper end of the shaft 58 is provided with a bevel gear 60 which in turn meshes with a bevel gear 62 formed on the lower end of the shaft 42. The gear 60 is provided with a collar 61 through which passes a pin 63 for securing the gear 60 to the shaft 52. The lower face of the collar 61 bears against the top of the bearing 59 thus preventing downward movement of the shaft 58. In order to eliminate excessive binding or friction between the gears 60 and 62 a ball thrust bearing 64 is interposed between the gears 60 and 62, as shown in Fig. 1.

By the use of this arrangement of gears the horn button 24 remains stationary relatively to the fastening inserting instrumentalities of the machine but the horn 21 is arranged to rotate relatively to the horn button 24. In order to accomplish this result, the ratio between the number of teeth on the gear 46 and the number of teeth on the gear 56 is equal to the ratio between the number of teeth 41 formed on the lower surface of the horn button 24 and the number of teeth 43 on the gear formed on the upper end 75

of the shaft 42. Assuming now that the horn 21 is rotated in a clockwise direction the gear 46 being stationary will cause the gear 48 which is carried by the horn 21 to rotate in a clockwise direction, and the gear 56 meshing with the gear 48 will rotate in a counterclockwise direction. This counterclockwise movement is transmitted through the shaft 53 to the gear 62 and the shaft 42. The gear teeth formed on the upper end of the shaft 42 will rotate the horn button 24 in a counterclockwise direction relatively to the horn 21 but since the horn is rotated an equal angular distance in a clockwise direction the rotation of the horn button 24 relatively to the driver 20 will equal zero. The horn button 24 thus remains stationary relatively to the fastening inserting instrumentalities irrespective of the rotation of the horn 21.

As previously stated, in order to maintain this stationary condition of the horn button there must be a certain relation between the parts. The ratio between the number of teeth on the gear 46 and the teeth on the gear 56 must equal the ratio between the teeth 41 on the horn button 24 and the teeth 43 on the upper end of the shaft 42. That is to say, if the gear 46 has forty teeth and the gear 56 has ten teeth the number of teeth on the horn button 24 and on the upper end of the shaft 42 must be in the ratio of four to one. It is apparent that the ratio could be three to one or five to one or in fact any other ratio consistent with good design. The number of teeth on the gear 48 is immaterial but it is evident that the gear 48 must be of such a size as to fit between the gears 46 and 56.

Although the clenching cavity 32 may be formed as a part of the horn button 24 it has been found to be preferable to form the clenching cavity in a separate member 66. Thus, when the clenching cavity 32 has become worn a new member may be substituted conveniently and inexpensively without necessitating the removal of the entire horn button 24.

It is to be understood that although the horn 21 has been referred to as being rotatable and in fact is rotated while the fastenings are driven into a shoe mounted on the horn the rotation of the horn is effected not through any conscious effort on the part of the operator but is rotated by engagement with the work to permit the tip of the horn to reach or engage the edge of the inside of the shoe, that is to say, when fastenings are being inserted adjacent to the side of the shoe the horn will swing an amount sufficient to permit the edge of the anvil to engage the side of the shoe. It is important, therefore, that the friction between the horn post and its bearings be reduced to a minimum. The upstanding projection 36 of the column of the machine, as shown in Fig. 1, is provided with a bearing 72 which surrounds a portion of the horn post 34. Interposed between the top of the bearing 72 and the horn 21 is a roller bearing 74 which minimizes friction between the horn post and the top of the bearing 72. The lower end of the horn post is provided with a bearing 76 which prevents radial movement of the horn post and thus prevents binding of the horn post in the bearing 72.

The present embodiment of the invention has been illustrated as clenching the ends of the fastenings substantially parallel with the edge of the shoe. It is apparent, however, that the ends of the fastenings could be clenched at substantially right angles or normal to the edge of the shoe by changing the position of the center of

the clenching cavity relatively to the horn button substantially 90°.

The invention has been described in detail and the principle and method of operation carefully and fully discussed but it is believed to be desirable to describe briefly the operation of the machine.

When the shoe 26 has been placed on the work support and the machine started, the awl 12 will move downwardly to form a fastening receiving hole in the work and then will move parallel to the bottom of the shoe to feed the work a distance sufficient to bring the fastening receiving hole into alignment with the driver 20. A fastening will then be inserted into the hole by the driver 20. The point of the fastening will strike the clenching cavity and will be deflected in a predetermined direction by the clenching cavity 34 in the horn button 24. As the fastenings are being inserted in the work the horn is rotated in locating the shoe in operative position relatively to the fastening inserting means but, due to the gear connections between the horn button 24 and the frame of the machine, the horn button will remain stationary relatively to the fastening inserting instrumentalities and each fastening, therefore, will strike the clenching cavity 32 at approximately the same point and the point of each fastening will be deflected in the same direction. It is to be understood that between the insertion of successive fastenings pressure on the horn is released to permit the shoe to be fed past the driver.

Although the present invention has been described and illustrated as particularly adapted to drive nails, it is apparent that tacks or other driven fastenings could be inserted and similarly clenched in one direction, if so desired.

Having thus described my invention, what I claim as new and desire to secure by Letters Patent of the United States is:

1. A machine for inserting fastenings having, in combination, a driver, a work supporting horn, a clenching anvil rotatably mounted on the tip of the horn, said anvil being provided with an elongated clenching cavity extending along one edge thereof and having its deepest portion offset from the path of movement of the driver, and means for maintaining the anvil and the clenching cavity in a predetermined position relatively to the driver to deflect the points of fastenings in a predetermined direction.

2. A fastening inserting machine having a driver, a rotatable work support, an anvil mounted on said support and provided with a relatively small elongated clenching cavity, the deepest portion of which is offset from the line of operation of the driver, to determine the direction of clench of the fastenings inserted by the driver, and gearing for maintaining the clenching cavity and said anvil in a predetermined position relatively to said driver.

3. In a fastening inserting machine, a rotatable work support, a driver, an awl adapted to punch a hole in a work piece and to feed the work piece into operative position with relation to the driver, an anvil carried by the work support, and means for holding the anvil against rotation with the support, said anvil having an inclined clenching face extending along the direction of the work feed.

4. A machine for inserting fastenings having a work support comprising a horn, a fastening inserting driver, an anvil rotatably mounted upon the tip of the horn and located in alignment with

the driver, the anvil having an inclined clenching surface bounded by straight walls, and means for maintaining the anvil with its clenching surface in a predetermined position relatively to said driver to insure clenching of the fastenings in a predetermined direction.

5. A fastening inserting machine having, in combination, a driver for inserting fastenings in a work piece, a horn rotatably mounted in the machine and arranged to extend into the inside 10 of a shoe to support the shoe in proper relation to the driver, a horn button rotatably mounted at the upper end of said horn, said horn being provided with an elongated clenching surface 15 having its deepest portion offset from the line of operation of the driver, and means interposed between the machine frame and the horn button for maintaining the horn button and the clenching cavity in a predetermined position relatively 20 to the driver to deflect the points of the fastenings

in the same direction for all positions of the horn.

6. In a fastening inserting machine, a driver for inserting fastenings into a work piece, an awl adapted to form fastening receiving holes in the work piece and to feed the work piece to the driver, a work supporting horn rotatably mounted in the machine for supporting the work, a horn button rotatably mounted on the end of said horn, said horn being provided with clenching surfaces arranged to insure that the points 10 of the fastenings will be deflected in the direction of the feed of the work piece, and gear connections between said horn button and the frame of the machine constructed and arranged to maintain the horn button and the clenching surfaces 15 therein in a predetermined position relatively to the driver and to the awl, thereby insuring that the fastenings will be clenched in a predetermined direction.

FRED N. LA CHAPELLE. 20
